UNITED STATES PATENT OFFICE.

ANDREW H. STONE, OF KANSAS CITY, MISSOURI.

EXTENSION-TABLE.

1,346,276.

Specification of Letters Patent. Patented July 13, 1920.

Application filed July 7, 1919. Serial No. 309,087.

To all whom it may concern:

Be it known that I, ANDREW H. STONE, a citizen of the United States, residing at Kansas City, in the county of Jackson and State of Missouri, have invented certain new and useful Improvements in Extension-Tables, of which the following is a specification.

My invention relates to improvements in extension tables; and my object is to provide a table of this character which may be used to advantage in apartments of limited space and wherever it is desirable to have a table that can be adjusted to occupy a small space or extended to give additional capacity when needed.

The table may be used to advantage in dining rooms, libraries, parlors, etc., and embodies one or more drawers in which the extension leaves are folded when not in use, said drawers when pulled out serving to support the leaves in extended position as will hereinafter appear, reference being had to the accompanying drawings, in which:

Figure 1 is an inverted plan view of the table with one of the leaves in extended position.

Fig. 2 is a broken longitudinal section on line II—II of Fig. 1, showing a latch and associated parts to hold the extended leaf in alignment with the table top.

Fig. 3 is a broken longitudinal section on line III—III of Fig. 1, showing a catch for holding the extended leaf firmly in engagement with the top of its support.

Fig. 4 is a detail perspective view of a drawer and one of the leaves associated therewith.

Fig. 5 is a broken front elevation of the table with the drawers and their contents and the legs at one end of the table removed.

Fig. 6 is a broken detail perspective of two of the legs; an end rail to which said legs are rigidly secured, and a pair of hooks for detachably securing the legs to the table.

Fig. 7 is a vertical longitudinal section of the table with the lower portions of the legs broken away.

Fig. 8 is a cross section on line VIII—VIII of Fig. 1, with the lower portion of the legs broken away.

Fig. 9 is a fragmentary longitudinal section on line IX—IX of Fig. 1.

Fig. 10 is a fragmentary inverted plan view partly in section of one of the table legs and associated parts.

The main frame of the table consists of the table top 2, two end rails 4, and legs 6, which are rigidly and permanently connected to said end rails 4 and removably connected to the table top 2.

The secondary frame of the table consists of two longitudinal bars 8, two end plates 10 to which said bars 8 are rigidly secured by suitable means such as screws 12, a pair of strips 13 secured to the undersides of the end plates 10, and a centrally-disposed bar 14 secured at its ends to the bars 8. Vertical right angular recesses 15 are formed in the terminals of the end plates 10 to receive the upper portions of the legs 6.

The end plates 10 are firmly secured to the underside of the table top 2 by suitable means such as screws 16, the heads of which bear against washers 18 at the lower ends of vertical holes 20 in said end plates 10 to freely admit the screws 16. By making the holes 20 large enough to freely admit the screws 16, the table top 2 may expand and contract independently of the end plates 10, without cracking or otherwise becoming damaged.

In order that the table may be rendered compact for shipment, or storage the end rails 4 and the legs 6 are detachable from the table top 2 and the end plates 10. This is accomplished by providing the legs with swiveled hooks 22, provided at their free ends with upturned loops 24 adapted to pass through apertures 26 in the two longitudinal bars 8 and be secured by suitable means such as screws 28. The hooks 22 are assisted in holding the end rails 4 and the legs 6 firmly in position by retaining members 30, which are firmly secured to the table top 2 and the end plates 10 and have downturned terminals 32 which enter grooves 34 in the upper ends of the table legs 6.

The end plates 10 have upper and lower slideways 34 and 36, respectively, separated by division strips 38, and the intermediate bar 14 is provided with a pair of parallel slideways 40 and 42 separated by a division strip 44.

Skeleton drawers 50 and 50^a are slidably mounted in the aforementioned slideways and as said drawers are substantially alike only one will be described in detail, the other being correspondingly numbered with exponents "a." As shown more clearly on Fig. 4, the drawer 50 consists of a front

- plate 54, a pair of slides 56 extending rearwardly from said front plate 54, an intermediate slide 58 paralleling the slides 56, side pieces 60 fixed to the inner surfaces of the slides 56, and a strip 62 connected to the slides 56 and 58 intermediate their ends. One of the side pieces 60 constitutes one side of a small compartment 64, arranged in one of the front corners of the drawer 50 to receive cards, games and other articles.
- The slides 56 and 58 operate in the slideways 34 and 42, respectively, and the slides 56^a and 58^a operate in the slideways 36 and 40, respectively. By arranging the slideways and the slides as aforementioned, said slides may pass each other when the drawers at opposite sides of the table are pushed inwardly and hence the table can be made more narrow and compact than if the ends of the slides met at the center of the table. The drawers may be rendered almost invisible when closed by dispensing with knobs and other exterior means for pulling them out, in which case the strip 8 is provided with recesses 63 and the rear lower edge of the drawer plate 54 is beveled as indicated at 65, to afford finger holds whereby the drawer may be pulled out, but if preferred knobs 65^a may be used.
- The drawers 50 and 50^a are provided with foldable extension leaves 66 and 66^a, respectively, and as said leaves and their fittings are alike only one will be described in detail, the other being correspondingly numbered with exponents "a." The leaf 66 consists of two sections 68 and 70, connected at one end with hinges 72. The section 70 is provided with fixed plates 74, which are pivotally and slidably mounted upon a rod 76 supported by plates 78, one of which is secured to one side of the compartment 64 and the other to one of the side pieces 60. When the leaf 66 is folded in the position disclosed on Fig. 7, its sliding movement on the rod 76 is limited by a sleeve 80 bearing against one of the plates 78, and a reinforcing block 82 secured to one of the side pieces 60 and the strip 62. Reinforcing blocks 83 are also employed at the juncture of the strip 62 and the side pieces 60.
- The leaf 66 is extended by pulling out the drawer 50, whereupon said leaf is swung one-half of a revolution on the rod 76 from the position disclosed on Fig. 7, to the position disclosed on Fig. 4. The section 68 is then swung one-half of a half revolution to the left on the hinges 72 to bring said section 68 in alignment with the section 70. The aligned sections 68 and 70 are then slid to the right to cause a catch 84 fixed to the underside of the section 68 to engage under a plate 86 countersunk in the upper left hand portion of the drawer 50. When this occurs a gravity latch 88, pivoted to a metal fitting 90 on the underside of the leaf sec-

tion 68, engages the inner edge of the plate 86 and thus coacts with the catch 84 in holding the extended leaf firmly in position upon the drawer 50. In order to allow the latch 88 to pass freely over the plate 86 when the extended leaf 66 is slid to the right, the front lower portion of said latch is beveled as indicated at 92 (Fig. 2), and a groove 94 is formed in the leaf section 68 to allow the latch to swing upwardly as it passes over the plate 86. A recess 87 is formed in one edge of the leaf section 68 to permit it to pass the slide 58 when the leaf 66 is swung to the position shown on Fig. 4.

The catch 84 and the latch 88 also hold the extended leaf in such position that its ends are in alignment with the table top 2. A lug 89 depending from the leaf section engages one corner of the drawer and coacts with the catch 84 and the latch 88 in holding the extended leaf in proper position upon the drawer. Should pressure be applied to the front portion of the leaf 66 while the same is in extended position its rear edge is prevented from springing above the abutting edge 9 of the table top 2 by means of a block 90, fixed to the underside of the leaf section 70 and projecting beneath the table top 2, as disclosed on Fig. 8.

Extreme outward movement of the drawer 50 is limited by a latch 96 and a stop 98. The latch 96 is pivotally mounted in a block 100 fixed to the underside of the strip 62. A handle 102 is formed at the front side of the latch 96, while a hook 104 is formed at the rear end of said latch 96. The hook 104 is slidably arranged in a groove 106 in one side of the slideway 42. Said groove 106 has a recess 108 into which the hook 104 drops and secures the drawer from outward movement after it has been pushed inwardly to bring the rear edge of the extended leaf 66 into engagement with the front edge of the table top 2. By reaching in under the drawer and pressing downwardly upon the handle 102 of the latch 96, the hook 104 is raised out of the recess 108, so that the drawer may again be drawn outwardly until said hook 104 contacts the stop 98 preparatory to folding the leaf 66. Should it be desirable to entirely remove the drawer from the table this may be accomplished by removing the stop 98, which is secured to the underside of the strip 8 by a screw 110.

The operation briefly stated is as follows: Ordinarily the folded leaf 66 rests upon the handle 102 of the latch 96 and prevents the hook 104 from entering the recess 108 and checking the free outward movement of the drawer 50. When the drawer 50 is pulled out until the hook 104 contacts the stop 98, the leaf 66 may be extended by rotating it a half revolution from the position shown on Fig. 7, to the position shown on Fig. 4, so that it will rest on top of the drawer 13

50 and the rod 76. The leaf section 68 is then rotated one-half of a revolution on the 65 hinges 72, after which said leaf is slid longitudinally on top of the drawer 50 and the 5 rod 76 until the catch 84 engages under the plate 86. This movement of the leaf also causes the free end of the latch 88 to pass over the plate 86 and engage its inner edge, so that said latch will cooperate with the 10 latch 84 in securing the leaf from longitudinal movement in either direction. The drawer is then pushed inwardly until the rear edge of the leaf contacts the front edge of the table top 2 in which position the leaf 15 is secured by the hook 104 dropping into the recess 108. When it is desired to close the drawer 50, the operator reaches under and depresses the handle 102 to raise the hook 104 from the depression 108. The 20 drawer is then pulled outwardly until checked by the stop 98, after which the extension leaf is folded into the drawer and the same is closed.

From the foregoing description it will be 25 understood that I have provided a table embodying the advantages above pointed out, and while I have shown and described the preferred form of my invention, I reserve the right to make such changes in the construction, proportion and arrangement of parts as properly fall within the spirit and scope of the claims.

Having thus described my invention, what I claim and desire to secure by Letters 30 Patent, is:

1. In a table of the character described, a table top, a frame to said top, a drawer 35 slidable in said frame, a foldable leaf mounted in said drawer and arranged to be supported in an extended position and in alinement with the table top by the drawer when the same is in an outward position, a catch on the leaf to engage the drawer and secure them from independent movement 40 when said leaf is in extended position, and a latch to coact with said catch in securing the leaf and the drawer together.

2. In a table of the character described, a table top, a frame to said top, a drawer 45 slidable in said frame, a foldable leaf mounted in said drawer and arranged to be supported in an extended position and in alinement with the table top by the drawer when the same is in outward position, a 50 plate secured to the drawer, a catch on the leaf to engage one side of said plate and hold the leaf and the drawer together, and a latch on the leaf to engage the opposite side of the plate and coact with the catch 55 when securing the leaf and the drawer together.

3. In a table of the character described, a table top, a frame to said top, a drawer 60 slidable in said frame, a foldable leaf

mounted in said drawer and arranged to be supported in an extended position and in alinement with the table top by the drawer when the same is in outward position, a plate secured to the drawer, a catch on the leaf to engage one side of said plate and hold the leaf and the drawer together, a pivoted latch on the leaf to engage the opposite side of the plate, and a lug depending from the leaf and engaging one corner of the drawer to coact with the catch and the latch in securing the leaf and the drawer from independent movement.

4. In a table of the character described, a table top, a frame to said top embodying superimposed slideways, two skeleton drawers one having slides in the lower slideways the other having slides in the upper slideways, and foldable leaves in said drawers arranged to be supported in extended position and in alinement with the table top by 85 the drawers when the same are in outward position.

5. In a table of the character described, a table top, a frame to said top embodying superimposed slideways, a support for the 90 frame and the table top, two skeleton drawers one having slides in the lower slideways the other having slides in the upper slideways, foldable leaves in said drawers arranged to be supported in extended position and in alinement with the table top by 95 the drawers when the same are in outward position, and means for securing the leaves from independent movement of the drawers when in extended position.

6. In a table of the character described, a table top, a frame to said top embodying superimposed slideways and two parallel slideways arranged beside each other, and drawers at opposite sides of the table one 100 having slides in the lower slideways and one of the parallel slideways the other having slides in the upper slideways and the other parallel slideway to allow the slides on one drawer to pass the slides on the other 105 drawer.

7. In a table of the character described, a table top, a frame to said top embodying superimposed slideways, two skeleton drawers one having slides in the lower slideways 115 the other having slides in the upper slideways, a rod mounted in each drawer, plates pivotally and slidably mounted on each rod, and foldable leaves mounted on said plates and adapted to be supported in extended 120 position and in alinement with the table top when the drawers are in outward position.

In testimony whereof I affix my signature, in the presence of two witnesses.

ANDREW H. STONE.
